(57) **CLAIM**

The ornamental design for a front panel area for a set-top-box, as shown and described.

DESCRIPTION

FIG. 1 is a perspective front view of the front panel area for a set-top-box;

FIG. 2 is a front view thereof; and,

FIG. 3 is a top view thereof.

The portion of the set-top-box shown in broken lines is for illustrative purposes only and forms no part of the claimed design.
